TOOL

William J. Luckins, Philadelphia, Pa., assignor,
by mesne assignments, to Minneapolis-Honey-
well Regulator Company, Minneapolis, Minn., a
corporation of Delaware

Application March 1, 1945, Serial No. 580,461

1 Claim. (Cl. 29—212)

1

The present invention relates to a tool for placing external cotters in a groove provided near the end of a shaft. Cotters of this type consist of a small disc-shaped piece of spring metal that is provided with a central opening and a slot leading to the opening. In use the slot in the c otter is placed over a groove that is turned near the end of the shaft on which it is to be placed. The c otter is then forced on the shaft. The opening in the c otter is made slightly smaller in diameter than the groove so that the c otter, when it is forced on the shaft, snaps in place and is held there by its own resilience.

It has been the custom in the past to hold each c otter by hand in the groove in the shaft and to force it on the shaft by means of a pair of pliers. All too frequently the c otter would slip and the operation would have to be started over again with the resultant loss of time. The manual setting of the cotters was particularly difficult where several parts were placed on a shaft under tension such as holding several parts in frictional engagement by means of a spring. In such cases it was quite often necessary to make a fixture to hold the parts in position on the shaft while the c otter was being set.

It is an object of the invention to provide a tool which will facilitate the setting of external cotters on shafts. It is a further object of the invention to provide a tool which will hold a plurality of cotters and which has a means to force these cotters into position in a groove formed adjacent the end of a shaft. The tool of the invention consists of a barrel which acts as a magazine to receive a plurality of the cotters. Attached to the barrel is a means to force individually each c otter upon a shaft, means, also attached to the barrel, being provided to receive and properly locate the end of the shaft upon which the c otter is to be placed.

The various features of novelty which characterize this invention are pointed out with particularity in the claim annexed to and forming a part of this specification. For a better understanding of the invention, however, its advantages and specific objects obtained with its use, reference should be had to the accompanying drawings and descriptive matter in which is illustrated and described a preferred embodiment of the invention.

In the drawings:

Figure 1 is a perspective view of the tool of this invention,

Figure 2 is a section through the tool,

2

Figure 3 is a view looking from the left in Figure 2,

Figure 4 is a view taken on line 4—4 of Figure 2, and

Figure 5 is a perspective view showing a shaft with a c otter attached thereto.

Referring to the drawings it will be seen best in Figures 4 and 5 that the external cotters 1 with which this invention deals are in the form of a circular disc of spring metal which is provided with a central opening 2 and a slot 3 extending from the outer edge to this opening. The c otter is also formed with a cut-away portion so that there is a bridge part 4 that gives 10 as the c otter is slid into position on the shaft. It is customary to make the opening 2 of slightly smaller diameter than the diameter of the slot in the shaft on which the c otter is to be placed. For example, if a shaft is to be used that is between 15 $\frac{1}{16}$ and $\frac{1}{8}$ inch in diameter, the groove in the shaft will be cut so that it has a diameter of 0.125", and the opening 2 in the c otter will be 0.122" in diameter. This means that the opening in the c otter is 0.003 smaller than the diameter of the groove in the shaft, so that the c otter will be retained in place by the natural resiliency of its bridge part 4.

The tool with which the present invention is concerned and which is used to place the c otter 20 in a suitable groove formed near the end of a shaft consists of a tube 5 which acts as a magazine for receiving a number of the cotters. This tube has a slot formed in it in which is inserted a wedge shaped key member 6 as shown in Figure 4. This key is adapted to receive the slot 3 of the cotters so that they will be held properly in position while they are in the tool and before being applied to a shaft. The cotters which have been placed within the tube or magazine are forced to the left in Figure 2 against a guide plate 9 that is fastened to the end of the tube. The force is applied to the cotters by a plug 7 that is in turn forced toward the left by a spring 8. It is noted that a cap 11 is provided on the 25 right end of the tube which serves to hold the spring in place. The supply of cotters in the magazine may be replenished by inserting them in the right end thereof after removing the cap 11, the spring 8 and the plug 7.

30 The front of the tube has a vertical slot 12 cut in it of a width equal to the external diameter of the cotters and of a depth equal to the thickness of one of the cotters. This slot taken in connection with the plate 9 that is attached 35 to the end of the tube serves as a guide for a

pushing member 13 that is operated to move the cotters downwardly in Figures 2 and 3 over a shaft which is suitably located in a manner to be described. Movement is imparted to the pusher member 13 by means of a support 14 that is attached to its upper end, which support is in turn fastened to a cylinder 15. The cylinder is guided for vertical movement on a rod 16 that is suitably attached to and extends from the surface of the tube. The cylinder is held on the rod by a screw 17 which extends into the rod and whose head serves to limit the outward movement of the cylinder. It will be seen from Figure 2 that the cylinder 15, the support 14, and the pusher member 13 are biased normally by a spring 18 to an upper position in which the lower end of the pusher member is slightly above the upper edge of the cotters as they are forced against the plate 9 on the left end of the tube. Attached to the bottom of the tube is an extension 19. It will be seen from Figures 1, 2, and 3 that a small recess 21 of a diameter equal to the maximum diameter of a shaft 22 upon which a cotter is to be inserted is drilled in the left faces of the key 6 and extension 19. This recess is of a depth such that a groove 23 formed near the end of the shaft will be lined up with the slot 12 that has been formed on the face of the tool.

In the operation of the device a shaft that is to have a cotter placed upon it will have its end inserted in the recess 21. Pressure will then be applied to the top of support 14 to move the pusher member 13 downwardly. This movement forces the cotter downwardly and permits it to spring over the shaft and be placed in the groove formed thereon. Since the tool is small and easily handled by an operator, it is only necessary for him to hold the tool against the end of a shaft and move the support 14 downwardly to put a cotter on the shaft. This operation is extremely simple and assures that each cotter will be held properly with respect to the shaft while it is being set thereon. If the shaft has on it several parts that are resiliently biased toward the end of the shaft and are to be held in place by one of these cotters, it is only necessary for them to be placed on the shaft and held in that position until the tool can be brought to bear against them. Movement of the tool against any members that are on the shaft will automatically push them back on the shaft the exact distance for the cotter to be placed thereon and will hold them in this position while that operation is taking place. It will be seen that no special fixtures are required to hold the parts on the shaft while the cotter is being placed thereon.

From the design of the tool it is obvious that different tools will be used with cotters of different diameters, since the barrel can only properly receive one size cotter and the shafts upon which it is to be placed. From the example given above it will be noted that there is a small variation permitted in the external diameter of the shaft for a cotter of a given size. The recess 21 will be of a diameter equal to the maximum diameter of the shaft that is to be used, and the small variation in diameter of the shaft

will not have any effect on the tool in the placing of the cotters.

While in accordance with the provisions of the statutes, I have illustrated and described the best forms of the invention now known to me, it will be apparent to those skilled in the art that changes may be made in the form of the apparatus disclosed without departing from the spirit of the invention as set forth in the appended claim, and that in some cases certain features of the invention may sometimes be used to advantage without a corresponding use of other features.

Having now described my invention, what I claim as new and desire to secure by Letters Patent is:

A tool for forcing a slotted disc cotter radially into an annular groove adjacent the end of a shaft, said tool comprising a barrel having a longitudinal bore therein constituting a magazine for the reception of a stack of slotted cotters in abutting face-to-face relation, a key extending longitudinally of said magazine adapted to engage the slots in said cotters and align them in proper position for use, a slot formed in one end of said barrel and extending transversely across the mouth of the magazine bore, said slot having a width and depth to slidably receive the endmost cotter of the stack of cotters, the wall of said barrel having therein a fixed open ended cylindrical recess of a diameter to snugly receive the end of the shaft to which the cotter is to be applied, the axis of said shaft-receiving recess being parallel to the axis of the magazine and the open end of said recess being flush with the bottom of said cotter-receiving slot, said recess having a depth equal to the lineal distance between the end of the shaft to which the cotter is to be applied and the groove therein so as to position the groove of a shaft inserted in said recess in alignment with said cotter-receiving slot, a plate having a flat outer face attached to the end of said barrel and extending across and enclosing said cotter-receiving slot for a portion of its length, pusher means slidably mounted in said cotter-receiving slot, said pusher means being normally in a retracted position out of alignment with said magazine bore but movable into engagement with the endmost cotter in said stack of cotters to eject said cotter from the magazine and move it across the open end of said shaft-receiving recess, and means to bias said pusher member to its retracted position.
